Des. 202,143
Patented Aug. 31, 1965

202,143

PHOTOGRAPHIC PROJECTION APPARATUS

André Victor Leon Clement Debrie, 111 Rue Sain Maur,
Paris, France

Filed Mar. 17, 1964, Ser. No. 79,037

Claims priority, application France Sept. 25, 1963

Term of patent 14 years

(Cl. D61—1)

FIG. 1

FIG. 2

FIG. 1 is a front perspective view of a photographic projection apparatus, showing my new design; and
FIG. 2 is a rear perspective view thereof.

The bottom of the machine, not shown, is plain and unornamented.

I claim:

The ornamental design for a photographic projection apparatus, as shown and described.
